Inventor:

Andrew Rankin

UNITED STATES PATENT OFFICE.

ANDREW RANKIN, OF NEW YORK, N. Y.

IMPROVED CHAMBER-VESSEL.

Specification forming part of Letters Patent No. 55,361, dated June 5, 1866.

To all whom it may concern:

Be it known that I, ANDREW RANKIN, of the city, county, and State of New York, have invented a new and useful Improvement in Vessels used for the Reception or Deposit, or both, of Offal, Excrement, Urine, or other Fecal or Waste Matter or Substances; and I do hereby declare that the following is a full, clear, and exact description thereof, which will enable others skilled in the art to make and use the same, reference being had to the accompanying drawings, forming part of this specification.

In the present instance my improvement in vessels used for the reception or deposit, or both, of offal, excrement, urine, or other fecal or waste matter or substances is illustrated in connection with the cover or lid for such vessels, although it can be adapted to some part or portion of the body of the vessels, the principle of this invention simply consisting in so forming such vessels or their covers or lids, or any part connected with either, as to adapt them to the reception and holding of any deodorizing or preservative material, substance, compound, or liquid for fecal and other refuse matter in a manner independent of and free from the fecal or other waste matter which the vessels may contain, in combination with so constructing such chambers or receptacles of the vessels or their covers or lids for the deodorizing or preservative agent used that at any time or times when so desired such agent can be discharged into the vessels in quantities more or less great, according as may be necessary to produce the required effect upon the fecal or other waste matter contained therein without opening such vessel or exposing its contents to the air, when by closing such communication the discharge of the preservative or deodorizing agent into the vessel can be stopped, as will be apparent from the following detail description of my invention, reference being had to the accompanying plate of drawings, wherein, for convenience of illustration and explanation, a lid or cover for the ordinary chamber pot or vessel is shown as constructed according to my improvement embraced herein—

Figure 1 being a plan view of the under side of the cover or lid for the chamber-pot, and Fig. 2 a central vertical section through the lid or cover, showing it placed upon a chamber pot or vessel, which is in vertical section.

A in the drawings represents a cover or lid of suitable shape and size to fit over and upon a chamber pot or vessel, which in Fig. 2 of the drawings is shown in vertical section, as before stated. This cover or lid A may be made of sheet-tin or other sheet metal, pottery, earthen or crockery ware, or other suitable material, and is made of a hollow or box shape, forming a chamber, B, to communicate with which from the outer or upper side of the cover A an orifice or nozzle, D, is made, that by means of a cork or other suitable stopper may be closed. In the bottom plate, E, of the lid a series of radial openings or slots, F, are made, to cover which a corresponding number and similar-shaped arms, G, but a little larger in size, are provided and attached to a common center spindle or shaft, H, turning in bearings of the lid or cover A, and projecting beyond and above the upper surface or side of the same, with a handle, I, upon such end for convenience in turning it, so as to bring its several arms G over the slots of the bottom plate, E, and thus close them, or to swing or move them away therefrom and thus open the same, this opening and closing of the said slots F being accomplished without necessarily removing the lid or cover from the vessel on which it may be placed or to which it may belong.

In the chamber or box B of the lid A, through its nozzle or orifice D, the preservative or deodorizing agent or agents used are placed, first having closed the slots in the bottom of the cover, when, stopping the said orifice or nozzle with a cork or other suitable device, the lid or cover is then ready for use upon the vessel to which it belongs, which in the present instance, as before explained, is to an ordinary chamber pot or vessel.

From the above description of the manner in which the lid or cover of the chamber-pot is constructed it is plainly apparent that when such cover or lid is upon the pot the deodorizing or preservative agent contained in it can be discharged into the pot in any desired quantities, whether large or small, and at any time or times, by simply turning the knob or handle of the spindle upon the outside of the cover in the proper direction therefor and without removing the cover or lid from the vessel or pot, when, a sufficient quantity having been so discharged into the said pot, the slots in the lid are then closed; and also that while the

preservative or deodorizing compound or agent used is contained in a chamber of the fecal vessel or pot entirely independent of and free from the fecal or other waste or refuse matter contained therein, it can be discharged into such fecal or waste matter at any time desired and in greater or smaller quantities.

It may be here remarked that, although the receptacle for the preservative or deodorizing compound or agent has been particularly explained as being located in the cover or lid of the vessel used as a receptacle or deposit for offal or other fecal or waste matter, it may be arranged in the body of the vessel, care being taken that it should be located at a sufficient height from the bottom of the vessel to enable the preservative agent contained in it to be discharged into the fecal or other waste matter within the vessel; and it may be still further remarked that, although my improvement has been herein particularly described with reference to the ordinary chamber pot or vessel, it can be adapted as well to other vessels, among which may be here mentioned as some of the most important the following, viz: bed-chair or

commode pans, slop-jars, slush or swill buckets or tubs, &c.; and that also it can be applied to the seats or benches of privies or water-closets, either arranged in their respective lids or covers or in the seats themselves; and therefore I do not intend to limit myself to the application of my improvement to any particular style of vessel or other receptacle, it being applicable to any vessel or receptacle for fecal or other waste or refuse matter or substances, as is obvious without any further explanation.

Having thus described my invention, what I claim as new, and desire to secure by Letters Patent, is—

The combination of the arms G and spindle H, operating relatively with the slotted plate F of the vessel B, having a nozzle, D, for the reception of the deodorizing agent, all arranged and applied in the manner herein described, for the purpose specified.

ANDREW RANKIN.
